United States Patent Office.

SAMUEL BABBITT, OF BRAZIL, INDIANA, ASSIGNOR TO HIMSELF AND
JOSEPH L. HUSSEY, OF SAME PLACE.

Letters Patent No. 105,161, dated July 12, 1870.

IMPROVEMENT IN AWLS.

The Schedule referred to in these Letters Patent and making part of the same

To all whom it may concern:

Be it known that I, SAMUEL BABBITT, of Brazil, in the county of Clay and State of Indiana, have invented a new and Improved Awl; and I do hereby declare that the following is a full, clear, and exact description thereof, which will enable others skilled in the art to make and use the same, reference being had to the accompanying drawing forming part of this specification.

Figure 1 represents a side view, partly in section, of my improved awl.

Figure 2 is a transverse section of the same.

Similar letters of reference indicate corresponding parts.

My invention relates to shoemakers' awls, and has for its object to change their form and construction.

The invention consists in forming a dovetailed recess in the awl, with a hook near the end thereof; in fitting into said recess a tenoned slide, and then fitting them both into a correspondingly-constructed handle.

A, in the drawing, represents the handle of the awl.

B is the awl. It is fitted into the handle, and has a backward-projecting hook, *a*, formed on it, some slight distance from its point.

b is a slide, fitted upon the awl, it having a T-shaped or dovetailed tenon, *c*, fitted into a groove of said awl. The slide can thus be moved back and forth on the awl, but cannot be lifted off. When pushed forward against the hook it closes the same, so as to form an eye, in which a thread is securely held.

For making or mending boots or shoes, this invention will be particularly useful. Thus the awl can be inserted through the leather, and can have its eye opened by drawing the slide back. Then the thread can be put into the hook on the inside, and the slide moved forward again to close the eye. The awl can then be drawn out with the thread. The face of the slide is roughened, to be readily and securely handled.

Having thus described my invention,

I claim as new and desire to secure by Letters Patent—

As an article of manufacture, a shoemaker's awl, consisting of needle B *a*, slide *b* *c*, and handle A, each constructed and relatively arranged as set forth.

SAMUEL BABBITT.
